UNITED STATES PATENT OFFICE

134,208

DESIGN FOR A SPOOL HOLDER

Eunice G. McCrary, West Point, Miss.

Application August 19, 1941, Serial No. 102,951

Term of patent 7 years

To all whom it may concern:

Be it known that I, Eunice G. McCrary, a citizen of the United States, residing at West Point, in the county of Clay and State of Mississippi, have invented a new, original, and ornamental Design for a Spool Holder, of which the following is a specification, reference being had to the accompanying drawing, forming part thereof.

Figure 1 is a view in top plan of a spool holder embodying my design.

Figure 2 is a view in side elevation thereof, and Figure 3 is a view in end elevation thereof.

The characteristic feature of my design resides in the specific decorations applied to each end of the spool holder, as shown.

I claim:

The ornamental design for a spool holder, substantially as shown and described.

EUNICE G. McCRARY.
